UNITED STATES PATENT OFFICE.

CHRISTIAN AALBORG, OF PITTSBURGH, AND FREDERICK C. WILHARM, OF HOMEWOOD, PENNSYLVANIA, ASSIGNORS TO WESTINGHOUSE ELECTRIC AND MANUFACTURING COMPANY, A CORPORATION OF PENNSYLVANIA.

OPERATING DEVICE AND DISCONNECTING SWITCH.

Application filed January 8, 1923, Serial No. 611,267. Renewed January 25, 1927.

Our invention relates to circuit interrupters and more particularly to the automatic operation of such circuit interrupters and their associated disconnecting switches.

5 One object of our invention is to provide a circuit-interrupter system in which the power device for actuating the circuit interrupters may also be employed for actuating disconnecting switches for the several circuit interrupters.

10 Another object of our invention is to provide mechanical means for preventing the operation of the disconnecting switches when the circuit interrupter is in a predetermined 15 operating position.

It is also an object of our invention to provide means for selectively connecting the mechanism for controlling the circuit interrupters or the mechanism for controlling the 20 disconnecting switches to a power device, as desired.

Figure 1 is a sectional view of a portion of a power station embodying our invention.

25 Fig. 2 is an elevational view of a set of disconnecting switches and certain related mechanism.

Fig. 3 is a diagrammatic view of the power device and its associated mechanism and circuits.

30 Fig. 4 is a side view, partially in section, of the apparatus for controlling the mechanical connections of the power device.

Similar reference numerals in the several 35 figures of the drawing indicate like parts.

In the preferred embodiment of our invention, a power station 1 has a plurality of floors or levels 2, 3, 4 and 5, between which project shelves 6. Between floors 2, 3, 4 and 5, are placed a plurality of circuit interrupters 7 which may be of any conventional type. The circuit interrupters 7 are connected, by a linkage mechanism 8 and a selective gear-shifting mechanism 9, to a power device 11 which may be, for example, an electric motor.

40 Between the several floors 2, 3, 4 and 5, and in cooperation with the several circuit interrupters 7, are placed a plurality of disconnecting switches 12 which are connected to, and controlled by, the linkage mechanism 8.

The linkage mechanism 8 comprises a pair of parallel coupling members 13 and 14 which extend vertically through floors 2, 3 and 4, and the several shelves 6. Coupling member 14 is adapted for the operation of the circuit interrupters 7 and has secured thereto, at suitable positions, a plurality of levers 15 which are respectively pivoted, as 55 at 16, to the several circuit interrupters for the purpose of operating the mechanism 17 which closes and interrupts the electrical circuit controlled by each circuit interrupter 7. At its upper end, coupling member 14 is secured to a pivotally mounted lever 18 that is adapted to be operatively connected to the motor 11 by the gear-shifting mechanism 9.

55 The coupling member 13 is connected, at its upper end, to a second pivotally mounted lever 19 that is also adapted for operative connection to the motor 11 by the gear-shifting mechanism 9. The several shelves 6 support a pair of bracket members 21 which, in turn, support a shaft 22, as is shown in Fig. 2. Mounted on the shafts 22, are a plurality of crank arms 23 that are operatively connected to the coupling member 13.

60 Keyed to the shafts 22, are a plurality of crank arms 24 which have pivotal connection to links 25, the latter having a direct pivotal connection to the several knife-blade switches 26 of the disconnecting switches 12.

65 Each disconnecting switch 12 comprises a pair of knife-blade switches 26, each of which is supported by a pair of insulators 27 attached to the walls of the power station 1. By means of this arrangement, each of the electrical conductors 28 connected to the circuit interrupter 7 may be disconnected, thereby completely de-energizing the circuit interrupter 7.

70 The gear-shifting mechanism 9 comprises a double-faced clutch member 29 that is slidably keyed on the motor shaft 30 and which coacts with clutch members 31 and 32 that are loosely mounted on the shaft 30. The clutch members 31 and 32 are respectively connected to cam members 33 and 34 which control the positions of the corresponding levers 18 and 19. The shiftable clutch member 29 is controlled by a pivotally mounted lever 35 having an arma-

ture member 36 at its outer end and being motor 11 and cam 33 to raise member 18 into its operative position.

The actuation of the lever 35 and the clutch member 29 to an operative position is effected by the one or the other of the electro-magnets 38 and 39 that are located upon opposite sides of the lever and adjacent to the armature member 36.

10 An interlock for preventing operation of the lever 19 unless the lever 18 is in a pre-determined position comprises a spring pressed plunger 51 which normally engages lever 19. An inclined projection 52 on the member 18 normally engages the plunger 51 to cause the latter to project into the path of the member 19, as is shown in Fig. 3.

15 The motor 11 is remotely controlled by switches 53 and 54. The switch member 53 coacts with contact members 55 and 56 while the switch member 54 coacts with contact members 57 and 58. The switch members 53 and 54 are so disposed that they engage contact members 55 and 57, respectively, in advance of the contact members 56 and 58, whereby the corresponding electromagnets 38 and 39 are energized prior to the closing of the motor circuit.

20 In the operation of a power station embodying our invention, the circuit interrupters 7 are frequently operated for the purpose of interrupting the circuits represented by conductors 28. It may be assumed that the lever 18 and the cam 33 occupy the respective positions in which they are illustrated in Fig. 4. In this position of the lever 18, the circuit interrupters are closed. In order to actuate the coupling member 14 to open the circuit interrupters, the operator actuates the switch member 53 to cause the latter to engage the contact members 55 and 56. The engagement between the switch member 53 and the contact member 55 causes energization of the electromagnet 38 which actuates the lever 35 to shift the clutch member 29 into engagement with the clutch member 31.

25 Engagement of the switch member 53 with the contact member 56 completes the motor circuit which comprises a source of energy 61. The motor then rotates the clutch members 29 and 31 and cam 33 in a counter-clockwise direction, as viewed in Fig. 4. At the proper point in the rotation of the cam 33, the lever 18 falls by force of gravity to cause a resultant operation of the circuit-interrupter mechanism 17. The switch 53 is then opened, de-energizing the motor 11 and the electromagnet 38, thereby allowing the lever 35 to move into a neutral position under the influence of the spring 37 that was placed under stress. If it is desired to close the circuit interrupters 7, the switch 53 is again closed to cause the

Such provision may be made that, during the travel of the member 18, the plunger 51 may be engaged by the projection 52 to lock the lever 19 in operative position or it may be disengaged therefrom to permit operation of the lever 19. In the mechanism shown in Fig. 3, provision is made whereby the member 19 and the controlled disconnecting switches 12 cannot be actuated when the circuit interrupters 17 are in their closed positions.

20 When it is desired to operate the disconnecting switches 12, and the member 18 is in proper position, movement of member 19 is permitted by the interlocking mechanism. The closing of switch 54 first effects energization of electromagnet 39, causing clutch member 29 to engage clutch member 32 and then complete the motor circuit. The cam 34 then raises or lowers the lever 19 in the same manner that the cam 33 actuates the lever 18. In case the lever 19 is lowered, motion is transmitted, through the coupling member 13 and associated mechanism, to the several disconnecting knife blades 26 to cause them to open, whereupon the circuit interrupters 7 are de-energized and rendered safe for repair purposes.

25 The opening or the closing of the disconnecting switches while the circuit interrupters are closed is prevented by the operation of the interlocking mechanism. We have provided a system of control for electrical circuit interrupters which requires but a single device for operating both the circuit interrupters and their associated disconnecting switches. In our system, we have provided a mechanism which prevents the operation of the disconnecting switches and the circuit interrupters in an improper sequence.

30 It will be apparent that various modifications in details and general arrangement may be made without departing from the spirit and scope of the invention, as defined in the accompanying claims. For example, if it is desired, the disconnecting switches and circuit interrupters may be interlocked in such manner that the former may be closed or opened only when the latter are closed. It will be understood that an electromagnet or other suitable electro-responsive device may be substituted for the electric motor, which is shown by way of example.

35 We claim as our invention:

1. In an electrical apparatus, a plurality of circuit interrupters at different levels, a disconnecting switch associated with each circuit interrupter, and a power device adapted to operate either said circuit interrupters or said disconnecting switches.

2. In an electrical apparatus, a plurality

of circuit interrupters at different levels, a disconnecting switch associated with each circuit interrupter, and a power device adapted to simultaneously operate either said circuit interrupters or said disconnecting switches.

3. In an electrical apparatus, a plurality of circuit interrupters, a disconnecting switch associated with each of said circuit interrupters, a power device, and means for selectively causing said power device to operate either said circuit interrupters or said disconnecting switches.

4. In an electrical apparatus, a plurality of circuit interrupters, a disconnecting switch associated with each of said circuit interrupters, a power device, and means for selectively causing said power device to operate either said circuit interrupters or said disconnecting switches and means for controlling the operation of said disconnecting switches with respect to the operative condition of said circuit interrupters.

5. In an electrical apparatus, a plurality of circuit interrupters, a disconnecting switch associated with each of said circuit interrupters, a power device, and means for selectively causing said power device to operate either said circuit interrupters or said disconnecting switches and mechanical means for controlling the operation of said disconnecting switches with respect to the operative condition of said circuit interrupters.

6. In an electrical apparatus, a plurality

of circuit interrupters, a power device adapted to operate said circuit interrupters or to control the connection of said circuit interrupters to an electrical circuit, and means for controlling the operation of the connecting means with relation to the operative condition of said circuit interrupters.

7. In an electrical apparatus, a plurality of circuit interrupters, a disconnecting switch associated with each of said circuit interrupters, a power device, and electrically controlled means for selectively causing said power device to operate either said circuit interrupters or said disconnecting switches.

8. In an electrical apparatus, a plurality of circuit interrupters at different levels, a disconnecting switch associated with each circuit interrupter, a power device, a mechanism adapted for connection between said power device and said circuit interrupters, a mechanism adapted for connection between said disconnecting switches and said power device, electrically controlled means for selectively causing said power device to actuate either the circuit interrupters or the disconnecting switches, and means for controlling the movement of the disconnecting switches with relation to the operating position of said circuit interrupter.

In testimony whereof, we have hereunto subscribed our names this 18th day of December, 1922.

CHRISTIAN AALBORG.
FREDERICK C. WILHARM.
